Primary Examiner — Garth Rademaker*Assistant Examiner* — Suzanne E Tisdell(74) *Attorney, Agent, or Firm* — Lee & Hayes, P.C.(57) **CLAIM**

The ornamental design for a vehicle fascia, as shown and described.

DESCRIPTION

FIG. 1 is a top, front, right side perspective view of a vehicle fascia;

FIG. 2 is an enlarged perspective view of the area marked 2 in FIG. 1;

FIG. 3 is a front view of the vehicle fascia; and,

FIG. 4 is an enlarged front view of the area marked 4 in FIG. 3.

The dashed broken lines depict portions of a vehicle that form no part of the claimed design. The dot-dashed broken lines represent the indication of the enlarged views and form no part of the claimed design.

1 Claim, 4 Drawing Sheets(56)
